SHOE SCRAPER

Tracy R. Wiltse, Des Moines, Iowa

Application December 1, 1949, Serial No. 130,521

1 Claim. (Cl. 15—237)

1
My invention relates to a device for removing mud and the like from shoes and boots and has combined with it a bootjack.

Shoe scrapers of one type or another are commonly used at homes and particularly on farms. They are very useful devices especially where out-of-doors work is necessary and the weather is damp or wet. However, most scrapers generally have only a scraper bar for the sole of the shoe and boot and sometimes a brush is provided for the sides thereof. In my device I have invented a novel type shoe scraper that is designed to remove mud and the like not only from the bottom of the soles of a shoe or boot but also from the top of the sole where it protrudes from the shoe and which also provides a brush for cleaning the side and top edges of the sole.

A further object of my invention is to provide a shoe and boot scraper of the above class that has a bootjack formed thereon so that after the shoes or boots have been cleaned they may be removed, if desired, without requiring the wearer to bend over or handle them.

A still further object of this invention is to provide a shoe scraper and bootjack that can be placed in the ground at any selected place or affixed to a step or the like without removing or adding any parts therefor.

A still further object of this device is to provide a shoe scraper of the above classes that is economical in manufacture, efficient in use and durable in construction.

These and other objects will be apparent to those skilled in the art.

My invention consists in the construction, arrangement, and combination of the various parts of the device, whereby the objects contemplated are attained as hereinafter more fully set forth, pointed out in my claim, and illustrated in the accompanying drawings, in which:

Fig. 1 is a perspective view of this device shown affixed to a door step or the like.

Fig. 2 is a cross-sectional view of this device taken on the line 2—2 of Fig. 1 with the dotted lines respectively showing the position of a shoe or boot on the scraper bar and engaging the bootjack, and

Fig. 3 is a front view of the upper part of one side of this device with the dotted lines respectively showing the position of a shoe or boot in engagement with the scraping brush and also being used on the spur scraper projection at the side thereof.

Referring to the drawings I have used the numeral 10 to designate two vertical spike or

2
stake members secured in spaced and substantially parallel relation by the transverse scraper bar 11, as shown in Fig. 1. A hole transversely through the center portion of each stake 10 is provided to receive a screw 12. The numeral 13 designates two projecting lugs or support arm members respectively secured to each of said stake members at a point above the hole for the screw 12 and extending at substantially right angles therefrom on the same side of each stake 10. A hole is provided in the free end portion of each arm 13 to receive a screw 14 and this device is designed to be capable of being mounted on a doorstep 21 or the like by means of the screws 12 and 14, as shown in Fig. 1 and Fig. 2.

The numeral 15 designates an outwardly extending scraper spur member that is provided on the top outside end portion of each stake member 10.

The inside upper portions of each of the stake members 10 is provided with a horizontal channel-like bracket member formed by the vertically spaced inwardly projecting arms 16 and 17 on each stake 10, as shown in Fig. 1. Each bottom arm 17 is flush with and disposed transversely to the top edge of the scraper bar 11. The numeral 18 designates two brush members respectively designed to be arranged in each of the channel brackets on the stake 10, as shown in Fig. 1, and to be detachably secured therein by means of the screw 19.

The center portion of the bottom longitudinal edge of the scraper bar 11 is cut away in the form of an inverted U and at the top center of this cut away portion a lip member 20 is provided which extends at substantially right angles therefrom in the same direction as the support arms 13.

Thus constructed and arranged this device can be used in the following manner: The scraper and bootjack can be placed anywhere in the ground by driving in the bottom portions of the stakes 10. It can also be detachably secured to any doorstep 21 or the like, as shown in the drawings. Once positioned it provides a means for removing all mud and the like from shoes or boots and also a means for removing the shoes or boots without requiring the wearer to stoop or bend or to handle the dirty foot gear.

When mud is caked about the soles, that part along the upper stitching on the sole can be easily removed on the scraper spurs 15, as shown in Fig. 3. The bottom of the soles can of course be cleaned on the scraper bar 11 and as this is done the brushes 18 will be slidably engaged by

the sides of the sole and any foreign matter thereon will be removed. Once the shoes or boots are cleaned, the heel portion can be placed under the lip 20 which serves as a bootjack to facilitate the removal. Also the circular concave portion of the bootjack can be used to scrape mud or the like from the back or heel portion of the shoe.

Some changes may be made in the construction and arrangement of my shoe service means without departing from the real spirit and purpose of my invention, and it is my intention to cover by my claim, any modified forms of structure or use of mechanical equivalents which may be reasonably included within its scope.

I claim:

In a device of the class described, two vertical spaced apart spike members each having pointed lower ends adapted to be driven into a holding medium, a vertical web scraper bar having its upper edge extending horizontally and extending between said two spike members and positioned below the extreme top planes of said spike members, a horizontal brush receiving and holding channel on the inside top portion of each of said spike members and located immediately above said scraper bar, a laterally extending lug on each of said spike members located in a plane below said scraper bar adapted to engage a horizontal object for holding said spike mem-

10

30

bers respectively against movement relative to said object in at least one direction, each of said spike members having a transverse hole in its length and below the plane of its lug adapted to receive a fastening means for securing said spike members respectively to a vertical object; said spike members, scraper bar, said brush receiving holding channels and said laterally extending lugs being integrally formed and of one piece.

TRACY R. WILTSE.
